FARM GATE

Neal T. MacKenzie, St. Paul, Minn., assignor to
 General Timber Service, Inc., St. Paul, Minn.,
 a corporation of Delaware

Application August 17, 1942, Serial No. 455,092

4 Claims. (Cl. 256—26)

It is an object of this invention to provide an improved and novel gate of the long rail type commonly used on farms.

A particular object is to provide novel and readily operable means for changing the elevation of the latch ends of such gates to compensate for sagging and for sloping ground.

Gates of this general character, due to their great horizontal extent (ordinarily from 10 to 16 feet), are difficult to maintain at the proper elevation at their latch or free ends. Neither the hinge supports nor gates themselves are sufficiently rigid as ordinarily constructed to retain the free ends in proper, substantially horizontal position for long. The present invention affords an unusually strong gate combined with readily operable means for adjusting the elevation of the free end of the gate.

The invention will be best understood by reference to the accompanying drawings in which:

Figure 1 is a side elevation of my improved gate;

Fig. 2 is a plan view of the same;

Fig. 3 is a fragmentary horizontal section taken on the line 3—3 of Fig. 1 and on a larger scale;

Fig. 4 is a part vertical section and part elevation showing one form of my adjusting device and the adjacent members;

Fig. 5 is a fragmentary section taken on the line 5—5 of Fig. 4;

Fig. 6 is a part vertical section and part side elevation showing an alternate form of my adjusting device and hinge;

Fig. 7 is a plan view of the portion of the gate and post shown in Fig. 6, and

Fig. 8 is a section taken on the line 8—8 of Fig. 6.

The principal members forming my improved gate comprise a series of spaced parallel rails 9 connected by stiles 10, 11 and 12 and a pair of diagonal brace members 13, all constructed from wood. The ends of the rails 9 are connected to the stiles by pivot pins 14 and 15 and the stiles are formed with mortises or recesses to receive the rails. The center stile 11 has mortises extending horizontally therethrough to receive the rails which are severally joined to the stile by the pins 15. Nails or bolts may be substituted for the wooden dowel pins shown.

Extending diagonally in parallel relation to each other from the lower end of the stile 12 to the upper end portion of the stile 10, the braces 13 are fastened to the stile 12 by a pin 16 and to the stile 10 by a pin 17. As best shown in Figs. 4 and 5, the pin 17 is adjustable in a slot 18 formed in the stile 10, this slot extending longitudinally of the brace members. The pin 17 may be constructed from wood and held in place by wedge shaped keys 19 fitting in slots extending through the pin adjacent to the outer faces of the respective brace members 13. The position of the pin 17 in the slot 18 may be adjusted by inserting one or more shims 20 between the pin and an end of the slot.

Hinges of conventional type may be used for supporting the gate or the hinges may be constructed from hard wood, as indicated in Figs. 3 and 4, or from metal, as shown in Figs. 6 and 7. As shown in Figs. 3 and 4 similar wood members 21 and 22 are formed to embrace the stile 10 and to be secured thereto by suitable bolts or nails such as the bolts 23 and the nails 24 and a bearing for a hinge pin 25 is also formed in the members 21 and 22. To support the gate a post 26 has its lower end anchored in the ground in conventional manner and a vertical bar 27 is spaced from the post by a member 28 and formed at its end with the hinge pins 25, one projecting up and the other down.

The free end of the gate is provided with a suitable latch 29 which is mounted on the stile 12 and arranged to engage a post 30. A stop member 31 projects from the post 30 for engagement with one side of the gate. The latch member 29 comprises a horizontally extending bar formed with an elongated slot 32 through which spaced bolts 33 extend to confine the latch on the gate and permit the necessary sliding movement to and from a recess in the post 30.

The alternate form of adjusting device shown in Figs. 6, 7 and 8 comprises a metal pin 34 which is movable in an elongated slot 35 similar to the slot 18. A bolt 36 extends at right angles to the pin 34 and is threaded in a cross bore formed in the latter. The head of the bolt 36 is accessible from the outer edge of the stile 10, where a suitable washer is interposed between this head and the stile. The ends of the pin 34 project through holes in the braces 13 respectively and are threaded to receive nuts for fastening the braces to the stile 10. By turning the bolt 36 the position of the pin 34 in the slot 35 may be adjusted to thereby raise or lower the stile 12 relative to the stile 10. The braces 13 are fastened to the center stile 11 by a bolt 15a which projects from slots 13a formed in the braces, these slots being elongated longitudinally of the braces so that limited longitudinal movement of the braces relative to the stile 11 is allowed.

Various types of metal hinges may be substi-

tuted for the wooden hinges shown in Figs. 1 to 4 inclusive, one metal substitute being illustrated in Figs. 6 and 7. As here shown, each hinge comprises a cap screw 37 adapted to project from the post 26 and formed with an upturned end 28 constituting a hinge pin. Hinge plates 39 are bolted to the stile 10 and formed with bearings for the pins 38.

To adjust the elevation of the free or latch end of the gate with the form of my invention shown in Figs. 1 to 5 inclusive, it is only necessary to remove one of the wedge keys 19 and to spring the end of the brace 13 free of the pin 17 while the latch end of the gate is raised and one or more of the shims 20 are inserted in (or removed from) the slot 18 thus bringing the free end of the gate to the proper elevation. Thereafter the brace member 13 is returned to engagement with the end of the pin 17 and the key 19 is replaced to make the fastening.

With the form of my invention shown in Figs. 6, 7 and 8, it is only necessary to turn the head of the bolt 36 to move the bolt 34 in the appropriate direction to either decrease or increase the effective length of the braces 13 and thereby either raise or lower the free end of the gate. The several rails fit loosely enough in the mortised stile recesses to allow this movement and the several pivotal connections between the rails 9 and the stiles 10, 11 and 12 and the sliding connection of the bolt 15a in the slots 13a permit the necessary change in the relative positions of the several members.

Having described my invention, what I claim as new and desire to protect by Letters Patent is:

1. A gate comprising substantially parallel vertically spaced rails, stiles for connecting the rails, connections between each rail and said stiles permitting changes in the elevation of one stile relative to another, a diagonal brace comprising a wood member of substantial width extending from the lower end portion of one of said stiles to an upper end portion of another stile, at least one of the stiles being formed with an elongated slot to receive a pin for fastening the brace thereto, a pin extending at a right angle to the gate in said slot for connecting the brace to the stile, said brace member concealing said slot and having a flat surface of substantial area abutting against a face of the stile, means engaging said pin to confine said brace member against the face of said stile and means for retaining said pin in various positions in said slot to adjust the angle of the gate relative to the horizontal.

2. A gate comprising substantially parallel, vertically spaced rails, stiles for connecting the

rails, pivotal connections between each rail and said stiles permitting changes in the elevation of one stile relative to another, a diagonal brace extending from the lower end portion of one of said stiles to an upper end portion of another stile, at least one of the stiles being formed with an elongated slot to receive a pin for fastening the brace thereto, a pin extending at a right angle to the gate in said slot for connecting the brace to the stile, said brace being perforated laterally to receive said pin and threaded means engaging said pin and stile for retaining said pin in various positions in said slot to adjust the angle of the gate relative to the horizontal.

3. A gate comprising, substantially parallel, vertically spaced rails, stiles for connecting opposite ends of the rails respectively, opposite vertical edges of the stiles being formed with recesses to receive the ends of the rails respectively, connections between the ends of each rail and the stiles permitting changes in the elevation of one stile relative to the other, diagonal braces comprising wide wood members extending in parallel relation to each other from the lower end portion of one of said stiles to an upper end portion of the other stile, said members overlapping opposite faces of one of said stiles and means connecting opposite end portions of the braces to the stiles respectively, at least one of said connecting means comprising a pin extending at a right angle to the gate through the overlapping portions of said brace members and movable longitudinally of the braces in a slot formed in the stile between the braces, said slot being elongated longitudinally of said brace and means for fastening said pin in various positions in the slot to adjust the angle of the gate relative to the horizontal.

4. A gate having in combination a plurality of rails connected by stiles, the several connections permitting limited pivotal movement of the rails relative to the stiles, a pair of braces extending obliquely across the rails and upon opposite outer surfaces of the stiles and means for changing the effective lengths of said braces to adjust the elevation of one of said stiles relative to another comprising a pin extending at a right angle to the gate through both braces and through a slot formed in the stile between the braces, said slot being elongated longitudinally of the braces, means for fastening said pin in various positions in the slot and a removable detent for confining at least one of the braces in engagement with said pin, said brace being adapted to be sprung free of the pin to allow access to said slot.

NEAL T. MACKENZIE.
